UNITED STATES PATENT OFFICE

111,841

DESIGN FOR AN AUTOMOBILE

Willard L. Morrison, Lake Forest, Ill.

Application October 21, 1936, Serial No. 65,394

Term of patent 7 years

To all whom it may concern:

Be it known that I, Willard L. Morrison, a citizen of the United States, residing at Lake Forest, in the county of Lake and State of Illinois, have invented a new, original, and ornamental Design for an Automobile, of which the following is a specification, reference being had to the accompanying drawing, forming part thereof.

Fig. 1 is a perspective view of an automobile showing my new design;

Fig. 2 is a sectional view, on a reduced scale, of the trim element shown in solid lines in Fig. 1, taken on line 2—2 of Fig. 1;

Fig. 3 is an enlarged sectional view taken on line 3—3 of Fig. 1.

The dominant features of my automobile design are indicated in solid black lines in the drawing. The other side of the design is substantially the same as the side showing in Fig. 1.

I claim:

The ornamental design for an automobile, substantially as shown and described.

WILLARD L. MORRISON.
